GEORGE ADOLPH STEINER, OF SALT LAKE CITY, UTAH.

TOWEL CABINET AND CLAMP.

1,169,297.

Specification of Letters Patent. Patented Jan. 25, 1916.

Application filed May 4, 1914. Serial No. 836,129.

To all whom it may concern:

Be it known that I, GEORGE ADOLPH STEINER, a citizen of the United States, residing at Salt Lake City, in the county of 5 Salt Lake and State of Utah, have invented certain new and useful Improvements in Towel Cabinets and Clamps; and I do declare the following to be a full, clear, and exact description of the invention, such as will 10 enable others skilled in the art to which it appertains to make and use the same, reference being had to the accompanying drawings, and to the letters and figures of reference marked thereon, which form a part of 15 this specification.

My invention relates to towel cabinets, and more particularly to a device of that character for use in hotels, or other places, where a number of towels are delivered at regular 20 intervals, and has for its principal object to provide a device of this character adapted for receiving a bundle of towels and retaining same in assembled relation while permitting individual use thereof. In accomplishing this object I have provided a cabinet 25 for containing the towels and a clamp for holding the towels in assembled relation, and which may be easily and quickly installed in the cabinet, or removed therefrom, 30 when a bundle of soiled towels is to be replaced by a fresh supply.

The preferred forms of the apparatus are illustrated in the accompanying drawings, wherein—

Figure I is a perspective view of a towel cabinet constructed according to my invention, showing a bundle of towels in the cabinet, and illustrating the position of the towels when a number have been used. Fig. 35 II is a vertical section of the cabinet, showing the initial position of the bundle of towels, and the clamping mechanism. Fig. III is a similar view showing the position of the towels and clamp mechanism, after a 40 number of towels have been used. Fig. IV is a detail perspective of the towel clamp. Fig. V is an enlarged front elevation of one 45 end of the clamp. Fig. VI is a detail perspective view of one end of a modified form 50 of clamp.

Referring more in detail to the parts: 1 designates the body of the cabinet, which 55 may be of any suitable construction, but preferably comprises an upper compartment

ber being open at the top and front in order to expose the towels for use, while protecting them at the sides and back. In each side of the compartment, near the open front, is a vertical groove 4 which extends downwardly a short distance from the top of the compartment and opens through the upper edges of the side portions thereof to receive the clamp trunnions 7. Fixed to the sides of the compartment, and extending thereacross, immediately back of the grooves 4, is an inclined shelf 5 for carrying the free ends of the towels, as will presently be described; the rear end of the shelf being spaced from the back of the compartment, 60 so that the towels may hang freely between the shelf and back.

The clamp which I prefer to use comprises a bar 6, having the trunnions 7 that are adapted for sliding and pivotal movement in the grooves 4, and a clamping bar 8 for coöperation with the bars 6 to hold a bundle of towels. Each of the bars 6 and 75 8 is preferably bulged at the center in order to compensate for any flexibility and insure 80 close contact of the bars with the towels throughout the length of the clamp. The bar 8 is provided near each end with a threaded sleeve 9, and mounted in each end of the bar 6 is a screw 10 which is adapted 85 for coöperation with the interior threads in the sleeve 9 to adjust the bars toward or from each other when the towels are to be placed in or removed from the clamp; each 90 of the screws being provided, at the outer face of the clamp 6, with a thumb nut 12, having a projection 13 provided with an aperture 14 for receiving the hasp of a padlock 15. Mounted on the bar 6, adjacent the thumb nuts, are staples or the like 16, for receiving the hasp of the padlock 15, so that 95 the nut may be locked in place to prevent loosening of the clamp and removal of the towels.

In the modified form of clamp shown in 100 Fig. VI, the screws are provided with square heads 17, and a plate 18 is pivotally mounted on a staple 19 on the bar and provided with a square aperture 20 and slot 21 for application to the square head of the 105 screw and to a staple 22 which is fixed in the bar 6 in position for coöperation with the locking plate. It is apparent that with this construction, when the plate is dropped over the square head of the screw and locked 110

to the bar by a padlock (not shown), the screw is held against displacement and the clamp bars held against the bundle of towels which is located therebetween.

5 In using the device, presuming the cabinet to be placed in the toilet-room of a hotel, or elsewhere, the person supplying the towels assembles each bundle at the laundry and the bundles are carried in units to the cabinets.

10 As the towels are counted before being assembled in the clamps, it is unnecessary for the distributor to count the towels at each delivery, as he need only place each bundle in one of the cabinets by dropping

15 the clamp trunnions into the grooves in the compartment at the top of the cabinet. It is readily apparent that the exchange of soiled towels for clean ones may be quickly made by merely drawing the clamp out of

20 the cabinet and dropping a fresh bundle in the place of the one which has been removed. When the fresh bundle of towels is placed in the cabinet, the free ends of the towels are thrown back over the shelf and

25 are supported thereon until removed for use. When the clamp is installed, the bar 6 is at the bottom, so that when the towels rest on the shelf, the friction between the towels and shelf holds the clamp in upright

30 position. As the towels are used and are dropped downwardly in the front of the cabinet, their weight gradually overcomes the friction between the clean towels and the shelf, so that the clamp edge of the

35 towel always faces the user, and the maximum area of the towel is made available for use. It is apparent that as the bundle is exhausted, the tilting movement of the clamp is increased, until when the weight of the

40 used towels is sufficient, the clamp hangs perpendicularly within the cabinet, with the bar 8 below the trunnion bar 6.

A cabinet of this construction not only facilitates the installation and use of

45 towels, but further insures against loss of the towels, as the latter are assembled and locked in the clamps at the laundry and can only be removed by a person having a

key to the lock by which the clamp bars are held together.

50

Having thus described my invention, what I claim as new therein, and desire to secure by Letters-Patent, is:—

1. The combination with a support, of a clamp comprising bars of unequal length, 55 with the bar of greater length pivotally mounted on the support, and the bar of lesser length carried by the longer bar, both of said bars being tapered from intermediate points toward their ends, for the 60 purpose set forth.

2. The combination with a suitable support, of a clamp comprising bars of unequal length, the ends of the bar of greater length being pivotally mounted on the support, 65 sleeves on one of said bars, screws on the other bar threaded into said sleeves to connect the bars, and means for locking said screws to maintain the locking connections between the screws and sleeves.

70

3. The combination with a cabinet having an open compartment, and having guide members at opposite sides of the compartment, a clamp comprising a supporting bar having trunnion members slidably and 75 pivotally mounted in said guide, and a clamping bar adjustably mounted on the supporting bar.

4. The combination with a cabinet having an open compartment provided with 80 facing grooves, of a clamp comprising a supporting bar having trunnion members adapted for sliding travel in said grooves and for pivotal support in the bases of the grooves, and a clamping bar of lesser length 85 than the supporting bar and having adjustable connection therewith, whereby the said clamping bar may move freely within the cabinet, substantially as set forth.

In testimony whereof I affix my signature 90 in presence of two witnesses.

GEORGE ADOLPH STEINER.
